ATTORNEY

UNITED STATES PATENT OFFICE.

IRA CASE, OF SAGINAW, MICHIGAN, ASSIGNOR OF ONE-FOURTH TO ARTHUR H. SWARTHOUT, OF SAME PLACE.

CUTTING APPARATUS FOR MOWING OR REAPING MACHINES.

SPECIFICATION forming part of Letters Patent No. 499,967, dated June 20, 1893.

Application filed March 21, 1892. Serial No. 425,695. (No model.)

To all whom it may concern:

Be it known that I, IRA CASE, a citizen of the United States, residing at Saginaw, in the county of Saginaw and State of Michigan, have 5 invented certain new and useful Cutting Apparatus for Mowing or Reaping Machines; and I do declare the following to be a full, clear, and exact description of the invention, such as will enable others skilled in the art to which 10 it appertains to make and use the same, reference being had to the accompanying drawings, and to the letters and figures of reference marked thereon, which form a part of this specification.

15 My invention is a cutting apparatus for reapers or mowers, and consists in the construction giving to the sickle a peculiar motion as it runs back and forth through the guards.

The object of my invention is to overcome 20 the loss of power caused by the sudden and complete stopping of the sickle after it has traveled its distance in the one direction, in order to set it going back again. As now made and used the sickle starts from one end of the 25 bar, travels to the other end, with great velocity when in actual use. Here it must come to a dead stop before it can return over the same track. It requires a great deal of force to stop it, and then it must be set in motion again from 30 a dead stop. The power employed in stopping it is necessarily lost so far as the result accomplished by the machine is concerned; and there is also a loss in power in having to start the sickle from its inertia at each end of the 35 throw. It is evident that any mechanism that will save this lost power will be valuable. This I claim to do in a great measure in the following described supporting bar and sickle.

Figure 1, is a top view of my device. Fig. 2, 40 is a top view of my device showing sickle in different position. Fig. 3, is an enlarged top view of the connection and elliptic groove. Fig. 4, is a side view of the fulcrum connection.

A is the sickle, and is of usual construction 45 except that I use a longer knife.

B is the supporting bar, provided with the usual guards, B', except that they are set differently. The front edge of the bar B is somewhat concave, and the guards B' are set on this 50 edge but at right angles to an imaginary horizontal line drawn through the middle of the

bar. This causes the points of the guards to have the same concave appearance, and as the sickle, unless it is given a circulinear motion, will not enter the guards at each end, I 55 give the sickle this said circulinear motion. In each end of the bar, B, I form elliptic grooves 1, 4. The ellipse is rather elongated or flattened at its sides, the end curves being more abrupt. The length of the ellipse should 60 be the distance from the center of one guard to the center of the other. In these grooves I place rollers, 2, 2, secured to the pin 2' 2', and these pins are secured in each end of the sickle A. I then adjust the sickle so that the 65 roller at one end thereof will be on the front side of the ellipse 1, and the knives on the sickle will engage the guards, B', at that end, and the other roller, at the other end, in the rear side of the ellipse 4 with the knives out 70 of the guards.

Upon the sickle A, at its center I form a longitudinal lug A', the length of the lug being about the length of the ellipse, 1. And at the center of the bar B, I secure the catch, 3, 75 for engaging this lug A', when the middle of the sickle has been placed in cutting position with the middle guards B'. Moving the sickle will cause the knives at the forward end to move through the guards from center to center, or until the rollers, 2, 2, have traveled the length of the sides of the ellipses 1, 4, when, if the power is continued the forward end will drop around the curved end of the ellipse and the other end advance through the curved end 80 of the other ellipse, bringing the knives at that end into cutting position. The center of the sickle by reason of its being fulcrumed at A', will keep between the guards.

B'', B'', are raised ribs on the bar B to support the sickle A and keep it from vibrating. The only friction there will be in the revolution of the sickle will be on the ribs B'' and the grooves, 1, 4. By using the roller 2, in each groove the friction there will be greatly 95 lessened.

E is the pitman connecting the sickle to the crank disk D by means of the joint F and the pin D'.

E' is an oblong slot in which the pin D' 100 moves and allows a free movement of the rod E as the crank disk and sickle revolve to-

gether, one circularly and the other elliptically.

C is the cover hinged to the bar B at C', C', and adapted to turn over upon the sickle and 5 guards to the cutting point thus preventing anything from getting into the knives or guards to clog them.

It will be observed that about two-thirds of 10 the sickle is brought into cutting position at each revolution of the sickle and that the ends 15 of the sickle cut but one way, and each the opposite of the other, but that the middle of the sickle cuts both ways. The number of revolutions that can be obtained by this motion 20 makes it unnecessary for the sickle to cut both ways. It will do all required of it operating as described.

Having thus described my invention, what 25 I claim as new, and desire to obtain by Letters Patent therefor, is—

1. A mowing machine cutting apparatus, comprising a supporting bar carrying guard fingers, elliptical grooves at each end of the bar, a sickle working in the guards and loosely 25 fulcrumed at its center to the bar, the fulcrum catch, and pins on the under side of each end of the sickle adapted to move in the elliptical grooves, substantially as described.

2. A mowing machine cutting apparatus 30 comprising a supporting bar, guard fingers, sickle, elliptical grooves in the supporting bar under each end of the sickle, a friction roller attached to each end of the sickle and working in the said grooves, a fulcrum catch at the 35 middle of the bar and sickle, loosely fulcruming the sickle at its middle whereby as one end of the sickle advances in its groove the

other recedes, and means for operating the sickle substantially as described.

3. A mowing machine cutting apparatus 40 consisting of a supporting bar carrying guard fingers, a sickle loosely fulcrumed at its middle to the middle of the supporting bar, and the rigid pitman secured to one end of the sickle at one end and to a horizontal crank 45 disk at the other, substantially as described.

4. A mowing machine cutting apparatus, consisting of the bar B having its front edge concave and the guards B' set on the same line as the front of the bar B, but at right angles to a straight line drawn through the said bar, and elliptical grooves, 1, 4, at each end of the bar, B, and sickle, A, having pins 2', 2', at each end bearing rollers 2, 2, running in the grooves 1, 4, and having the lug A', at 55 center of the sickle, and catch 3, for fulcruming the sickle, all arranged and operated substantially as described.

5. A mowing machine cutting apparatus comprising a supporting bar carrying guards, 60 elliptical grooves formed on bed of the supporting bar, friction rollers traveling in said grooves and carrying a sickle, a sickle loosely fulcrumed at its middle to the supporting bar, and a covering for the sickle and bar to the 65 base of the guard fingers substantially as described.

In testimony whereof I affix my signature in presence of two witnesses.

IRA CASE.
